TOOTHPICK

Glen E. Millard, St. Paul, Minn., assignor to Lactona Incorporated, St. Paul, Minn., a corporation of Minnesota

Application August 3, 1945, Serial No. 608,770

5 Claims. (Cl. 132—93)

1

My invention relates to an improvement in toothpicks and deals more particularly with a series of toothpicks integrally attached to a common base.

Toothpicks, when properly designed and correctly used, are of considerable assistance in properly caring for the teeth. In order to be of most service, however, the toothpick must be properly shaped. It is also important to form the toothpicks of a material best suited for the purpose. If the toothpicks are too hard or stiff they are likely to injure the surface of the teeth. On the other hand, if the toothpicks are too soft they do not produce the proper results.

It is an object of the present invention to form a series of toothpicks of molded plastic and attached to a common base. The toothpicks may be individually detached from the base when desired for use. As a result the toothpicks may be readily carried about without danger of losing the toothpicks.

A feature of the present invention resides in molding the toothpicks from a plastic to form a somewhat resilient body. The material forming the toothpicks is not extremely hard, nor is it extremely soft. The toothpicks will bend and flex readily without breaking and will return to their normal shape after flexure. By properly regulating the hardness of the body of the toothpicks an instrument may be produced which may be used to prevent the building up of deposit about the base of each tooth, as well as to remove foreign matter from between the teeth. The body of the toothpicks is sufficiently soft to serve admirably as a massaging element to massage the gum tissue at the base of the teeth.

It is a feature of the present invention to produce toothpicks having a relatively heavy section at one end which may serve as a handle end for the toothpick. The other end of each toothpick is tapered to a fine point and is substantially triangular in cross section to enter the interdental spaces which are also usually substantially triangular.

A further feature of the present invention lies in the manner of attaching the individual toothpicks to the common base. The handle end of each toothpick tapers to a relatively narrow line of connection between the sides of each toothpick. In removing each toothpick the handle end thereof is swung down toward the base. The tapering lower end of each toothpick may act as a fulcrum to assist in separating the toothpick from the base.

These and other objects and novel features of

2

my invention will be more clearly and fully set forth in the following specification and claims.

In the drawings forming a part of my specification:

5 Figure 1 is a top plan view of a series of toothpicks attached to a common base.

Figure 2 is a front elevational view of the toothpicks shown in Figure 1.

10 Figure 3 is a rear elevational view of the toothpicks shown in Figures 1 and 2.

Figure 4 is an end elevational view of the toothpicks and base.

15 The series of toothpicks on their integral base are designated in general by the letter A. The individual toothpicks 10 are shown secured at their handle end to a base 11 in a manner which will be described in more detail. The base 11 provides a means of supporting the toothpicks in vertical position as shown in Figures 2, 3, and 20 4 of the drawings, when it is desired. The base 11 includes an enlarged bottom plate 12 and an upstanding web 13 on the bottom plate. The web 13 is grooved on its front end and rear surface, the rear groove being indicated by the numeral 14 and the front groove being indicated by the numeral 15. The front groove 15 may contain a name, such as 16, formed of letters standing out in relief from the grooved portion of the web 13. The top of the web 13 is tapered inwardly at 16 and terminates in a flat upper surface 17. The toothpicks 10 are integral with the flat upper surface 11.

25 Each of the toothpicks 10 includes a handle portion 19 which is substantially rectangular in cross section and forms a relatively rigid handle body. This handle body 19 tapers inwardly from opposite sides of each toothpick so as to form a substantially triangular bottom end on each toothpick. The toothpicks are secured along a 30 relatively narrow line of attachment 20 at the lower end of this triangular end to the base surface 17.

35 This inwardly tapered end serves a double function. In the first place it provides a weakened line of connection between each toothpick and the base so that the toothpick may be readily removed. In the second place as each toothpick is removed it may be bent laterally as viewed in Figures 2 and 3 so that one flat tapered surface 40 rests against the upper surface 17 of the base. Any further pivotal motion of the toothpick tends to lift the connected end thereof away from the base, the line between the tapered lower end and the adjacent side of the toothpick acting as a 45 fulcrum point against the base 11. Thus the line

between each side of the tapered end and the adjacent side of the toothpick may be used as a fulcrum to assist in the separation of the toothpick from the base.

The upper end 21 of each toothpick is substantially triangular in cross section. At a point 22, substantially midway between the ends of each toothpick, the body begins to taper as viewed from the front or rear. This taper continues to the extreme tip end 23 of each toothpick. Near the point where the taper of the toothpicks begins, the sides of the toothpick body are beveled so that the toothpick is substantially triangular in cross section. As viewed from the rear edge, the toothpick is provided with a flat rear surface throughout its length and tapers from an intermediate point 22 to the tip end 23. As viewed from the front end, and as noted in Figure 2 of the drawings, each toothpick is provided with a center line 24 between two beveled sides 25. The beveled sides or surfaces 25 together with the flat rear surface forms the substantially triangular shape of the individual toothpicks.

As viewed from the side, each toothpick is curved slightly from its front surface 26 toward its rear surface 27. This gentle curve of the toothpick continues to a point 29 near the tip end 23. From this point to the tip end the toothpicks are beveled more sharply as indicated.

The toothpicks A may be made of various types of plastic and are preferably formed of a material which is resilient and flexible rather than extremely stiff. For example, my toothpicks may be made of various types of acetate plastics, some of which are harder than others. Other plastics such as rubber base plastics are suitable for my purpose. These plastics permit the tapered tip end of the toothpick to flex readily and to compress slightly. As a result the toothpick is soft enough to fit the interdental spaces and at the same time sufficiently hard to prevent the building up of deposit on the teeth.

When attached to the base the toothpicks may be supported in a vertical position upon the base or may be readily carried in a pocket or purse. When desired for use each toothpick may be separated from the base in the manner described and discarded after being used for its desired purpose.

In accordance with the patent statutes, I have described the principles of construction and operation of my toothpicks, and while I have endeavored to set forth the best embodiment thereof, I desire to have it understood that obvious changes may be made within the scope of the following claims without departing from the spirit of my invention.

I claim:

1. A toothpick construction comprising a base, a flat upper surface on said base, a series of solid bodied toothpicks integral with said base, each of said toothpicks including a substantially triangular connecting end and the apexes of the triangular ends being parallel, said toothpicks being connected to said base along an apex of said triangular connecting portion.

2. A toothpick construction including an elongated base including substantially parallel top and bottom members and a connecting web therebetween, the top member being substantially flat and having a series of solid bodied toothpicks connected thereto along spaced parallel transversely extending areas of connection, said toothpicks each having a handle portion, a tapered upper end portion, and a bluntly tapered bottom portion, said bottom portion extending substantially the full thickness of said handle portion of the toothpicks and bluntly tapered in width, and terminating in the laterally spaced areas of connection with said base.
3. A toothpick construction including an elongated base having a substantially flat upper surface, a series of solid bodied toothpicks connected to said flat upper surface to extend substantially normally thereto, each of said toothpicks including a handle portion, an elongated tapered free end portion, and a short bluntly tapered attached end, said attached end of each toothpick being substantially the full thickness of the toothpick and tapered in width terminating in an apex forming an elongated area of connection with the base, the areas of connection being spaced and parallel and extending transversely of the base.
4. A toothpick construction comprising an elongated base, a series of spaced solid bodied toothpicks integral with said base, and a wedge shaped end on each said toothpick the edge of which provides a relatively narrow connecting area between the base of the wedge shaped ends of said toothpicks and said base, said connected areas being at right angles to the longitudinal axis of the base and in spaced parallel relation.
5. A toothpick construction comprising an elongated base, a series of elongated solid-bodied toothpicks connected to said base to extend normally thereto, a tapered end on each of said toothpicks, the edges of said tapered ends being connected to said base along parallel relatively narrow areas of connection, said narrow areas being at right angles to the longitudinal axis of the base and in spaced parallel relation, said areas forming the sole contact between the toothpicks and the base.

GLEN E. MILLARD.
